(57) CLAIM

The ornamental design for an inner tube valve stem positioner, as shown and described.

DESCRIPTION

FIG. 1 is a side elevational view of the invention and it is to be understood that the other side elevational view is the same;

FIG. 2 is an end elevational view of the invention and it is to be understood that the other end elevational view is the same;

FIG. 3 is a top plan view of the invention; and,
FIG. 4 is a bottom plan view of the invention.
